UNITED STATES PATENT OFFICE.

HARRY R. DECKER, OF HOUSTON, TEXAS.

STRAINER FOR OIL AND WATER WELLS.

958,100.

Specification of Letters Patent. Patented May 17, 1910.

Application filed September 25, 1906, Serial No. 338,109. Renewed September 24, 1909. Serial No. 519,409.

To all whom it may concern:

Be it known that I, HARRY R. DECKER, a citizen of the United States, residing at Houston, in the county of Harris and State 5 of Texas, have invented certain new and useful Improvements in Strainers for Oil and Water Wells, of which the following is a specification.

The strainer in common use in oil wells 10 consists of a length of tubing with holes bored through it and either the tube wrapped with wire to form the strainer surface or perforated or slotted disks are secured in the holes and act as strainers. In 15 an accompanying application is described a process of drilling wells in which this strainer is used as the lower length of the drill tube and has the holes in the tube plugged with easily removed or broken 20 plugs so that when the oil or water stratum is reached the drill stem may remain permanently in the well bore and used as the last casing to be set in the well all that is necessary being to run a tool down the drill tube 25 and break the plugs and the plugged strainer becomes converted into an effective and operative strainer to perform the functions for which strainers are used in wells. In this application is described the strainer 30 used in this process which description will be found hereinafter and illustrated in the accompanying drawings in which—

Figure 1 is a fragmental longitudinal sectional view of a strainer of the disk class 35 showing my invention in connection therewith, Fig. 2, a similar view showing my invention applied to a wire wound strainer, and Figs. 3 and 4, views showing modifications of the strainer shown in Fig. 1.

40 In the drawings similar reference characters indicate corresponding parts in the various views.

A indicates the strainer tube in which is 45 drilled a number of holes B and either has perforated disks C secured therein as shown in Fig. 1, to act as strainers, or the tube is wound with wire D, as shown in Fig. 2, to 50 form the strainer surface. The wire wound strainer such as shown in Fig. 2 is a well known form of strainer while the disk strainer illustrated in Fig. 1 is the subject of my application filed August 1, 1906, and given Serial No. 328,748.

55 My improvement consists in forming each of the holes B in tube A with an inwardly projecting tapered shoulder E and provid-

ing thimble plugs F made of Babbitt metal or other easily fractured substance but which will have sufficient tensile strength to resist the pressure of the oil or water from 60 the outside. Each of the thimble plugs E are provided with a flange G that seats on shoulder E to retain it in position. It will be understood that the plugs F are secured in position before the disks C are installed 65 or the wire D wrapped on the tube and that the strainer will not operate until the plugs F are broken.

In Fig. 3 is shown a modification in which the shoulder is shown untapered, while in 70 Fig. 4 the holes in the strainer tube are straight and the plugs formed without flanges and retained by friction.

I do not claim in this application any 75 form of strainer but only the combination with a strainer of any type having a perforated tube as its base the securing of my thimble plugs in the holes in the tube.

Having thus described my invention what I claim is—

80 1. In combination with a strainer comprising a perforated tube, frangible plugs secured in the holes in the tube, substantially as shown and described.

2. In combination with a strainer comprising a perforated tube, imperforate thimble plugs secured in the holes in the tube, substantially as shown and described.

3. In combination with a strainer comprising a perforated tube, thimble plugs of 90 frangible material secured in the holes in the tube, substantially as shown and described.

4. In combination with a strainer comprising a perforated tube, frangible plugs 95 secured in the holes in the tube and extending inside of the inner surface of the tube, substantially as shown and described.

5. In combination with a strainer comprising a perforated tube, imperforate 100 thimble plugs secured in the holes in the tube and extending inside of the inner surface of the tube, substantially as shown and described.

6. In combination with a strainer comprising a perforated tube, thimble plugs of 105 frangible material secured in the holes in the tube and extending inside of the inner surface of the tube, substantially as shown and described.

7. In combination with a strainer comprising a tube having holes therein provided

- with shoulders, imperforate, frangible plugs secured in the holes in the tube having flanges to seat against the shoulders in the holes, substantially as shown and described.
- 5 8. In combination with a strainer comprising a tube having holes therein provided with shoulders, and frangible plugs secured in the holes in the tube having flanges to seat against the shoulders in the holes, sub-
- 10 stantially as shown and described.
9. In combination with a strainer comprising a tube having holes therein provided with shoulders, imperforate frangible thimble plugs secured in the holes in the tube
- 15 having flanges to seat against the shoulders
- in the holes, substantially as shown and described.
10. In combination with a strainer comprising a tube having holes therein provided with shoulders, and thimble plugs of frangible material secured in the holes in the tube having flanges to seat against the shoulders in the holes, substantially as shown and described.
- In testimony whereof I hereto affix my 25
signature in the presence of two witnesses.
- HARRY R. DECKER.
